UNITED STATES PATENT OFFICE.

BRYANT H. BLOOD, OF HARTFORD, CONNECTICUT, ASSIGNOR TO PRATT & WHITNEY COMPANY, OF NEW YORK, N. Y., A CORPORATION OF NEW JERSEY.

REVERSIBLE GAUGE.

Application filed April 8, 1922. Serial No. 550,748.

To all whom it may concern:

Be it known that I, BRYANT H. BLOOD, a citizen of the United States, residing at Hartford, in the county of Hartford and 5 State of Connecticut, have invented certain new and useful Improvements in Reversible Gauges, of which the following is a specification.

This invention relates to plug gauges and 10 particularly to an improved reversible plug gauge of the "go" and "not go" type. Gauges of this type usually comprise a handle having a "go" gaging head on one end and a "not go" gaging head on the 15 other end whereby the operator may conveniently first try the "go" gaging head and then the "not go" head if necessary. In my improved construction disclosed herein I provide a improved gaging head comprising both "go" and "not go" sections. 20 I propose to mount such gaging head on a single end of the handle and to make the head reversible relative to the handle in a manner to considerably lengthen the life of 25 the gauge. It is accordingly an object of my invention to provide an improved reversible plug gauge of the type.

It is another object of my invention to 30 provide an improved reversible gaging head comprising three sections, the middle section thereof being the "not go" portion of the head and the two outer sections being "go" portions.

More specifically it is an object of my 35 invention to provide a plug gauge comprising principally a handle and a gaging head, the gaging head comprising a middle "not go" section and a "go" section preferably integral with each end thereof, and the handle being adapted to be mounted on either end of the gaging head.

With the above and other objects in view, 40 my invention consists in the features of construction and operation set forth in the following specification and illustrated in the accompanying drawing. In such drawing annexed hereto and forming a part of this specification, I have shown one embodiment of my invention, but it will be understood that the same can be otherwise embodied and that the drawing is not to be construed as defining or limiting the scope of the invention, the claims appended to this specification being relied upon for that purpose.

Referring to the figures of the drawing: 55 Figure 1 is a side elevation of an assembled gauge comprising my invention.

Fig. 2 is a side elevation of the gauge handle.

Fig. 3 is a side elevation of the improved 60 reversible gaging head.

Fig. 4 is a side elevation of the means for securing the gaging head to the handle.

Figs. 5 and 6 illustrate end views respectively of the handle and gaging head. 65

Referring more specifically to the drawing by reference characters, 1 indicates the handle and 2 the gaging head of my improved reversible plug gauge. I have illustrated the gaging head as of tubular form 70 and as adapted to be secured to the handle by means of a bolt 3.

The gaging head 2 comprises three sections, namely, a middle "not go" section *a* and two outer "go" sections *b* and *c*. As 75 illustrated, the sections *b* and *c* are symmetrical, relatively long as compared to the middle "not go" section *a*, and are preferably integral with the said middle section *a*. It will be understood that the middle "not 80 go" section *a* is of a slightly greater diameter than the "go" sections *b* and *c* and the sections are preferably spaced from each other by annular grooves 4.

The gaging head 2 is reversible, that is, 85 either end may be secured to the handle 1. Means is provided for preventing relative rotation and looseness of the head on the handle and such means preferably comprises interengaging projections and notches 90 in the abutting ends of such elements. Each end of the head 2 is illustrated as being provided with three V-shaped radial grooves or notches 5 for receiving similarly shaped projections 6 on the end of the handle. When 95 the bolt 3 draws the head and handle into tight engagement, these interengaging projections and notches form a tripod support therebetween thereby preventing relative rotation and looseness between the head and 100 the handle.

I preferably provide the gauge with a pilot member at its gaging end. As illustrated this member comprises a conical bushing 7 mounted on the bolt and adapted to 105 be engaged between the head of the bolt and the gaging end of the head 2. The bushing 7 is also provided with a tooth 8 for seating

in one of the notches 5 to prevent relative rotation of the pilot relative to the gaging head.

For gaging purposes, the gauge is assembled as shown in Fig. 1. In operation, the operator holds the gauge by the handle 1 and inserts the other end of the gauge into the hole to be gaged, the pilot 7 assisting in this gaging operation. If the hole 10 is of the proper size, the "go" section *b* will enter the hole but the "no go" section *a* will be too large to enter. In use, the "go" section of the gauge, by contacting with the edges of the holes being gaged, becomes worn down much more quickly than the "no go" section and must therefore be frequently renewed. When the section *b* of the gauge illustrated has become so worn down, the bolt 3 may be removed and the gaging head 15 2 reversed end for end, that is, so that the handle is secured to the end of section *b*. The unworn section *c* then becomes the "go" end of the gauge in the same manner as was the end *b* and the gauge is thereby renewed 20 to a working condition equal to that of its original form. As will be obvious, because of this reversible feature the life of the gauge is doubled.

To assure proper positioning of the pilot member 7 so that it will be concentric with the forward end of the gaging member 2, I provide the bolt 3 with a slightly enlarged portion 9 adjacent its head. This portion 9 is ground or otherwise carefully finished 35 so that it will fit within the hole of the gaging member 2 and also within that formed in the pilot member 7. It will thus be seen that as the finished portion 9 of the bolt 3 enters both the pilot 7 and the forward end of the gaging member 2 that it serves to hold these two parts in accurate alignment.

What I claim is:

1. A cylindrical gaging head of the "go" and "not go" type comprising three sections, the middle section being of a slightly greater diameter than the end sections and acting as the "not go" section for an end section.
2. A cylindrical gaging head of the "go" and "not go" type comprising three integral sections, the middle section being of a slightly greater diameter than the end sections and acting as the "not go" section for both end sections.
3. A cylindrical gaging head of the "go" and "not go" type comprising a middle section and a relatively long section integral on each end thereof and spaced therefrom by an annular groove, the middle section being of a slightly greater diameter than the end sections and acting as the "not go" section for both end sections.
4. A tubular gaging head of the "go" and "not go" type comprising three integral sections, the middle section being of a slightly

greater diameter than the end sections and acting as the "not go" section for both end sections.

5. A reversible plug gauge comprising the combination of a three-part gaging head of the "go" and "not go" type, a handle adapted to be secured to either end of the head, and means for so securing the head to the handle, the middle section of the gaging head being of a slightly greater diameter than the end sections and acting as the "not go" section for both end sections.

6. A reversible plug gauge comprising the combination of a three-part gaging head, a handle adapted to be secured to either end of the head, screw threaded means for so securing the head to the handle, and means between the head and the handle for preventing relative rotation and looseness between the head and handle, the middle section of the gaging head being of a slightly greater diameter than the end sections.

7. A reversible plug gauge comprising the combination of a three-part tubular gaging head, a handle adapted to be secured to either end of the head, and a bolt adapted to extend through the head and thread into the handle for so securing the head to the handle, the middle section of the gaging head being of a slightly greater diameter than the end sections.

8. A reversible plug gauge comprising the combination of a three-part tubular gaging head, a handle adapted to be secured to either end of the head, a bolt adapted to extend through the head and thread into the handle for so securing the head to the handle, and means on the head end of the bolt for piloting the gauge in operation, the middle section of the gaging head being of a slightly greater diameter than the end sections.

9. A reversible plug gauge comprising the combination of a three-part gaging head, a handle adapted to be secured to either end of the head, means for so securing the head to the handle, and a plurality of interengaging projections and notches at the abutting ends of the head and handle for preventing relative rotation and looseness between the head and handle, the middle section of the gaging head being of a slightly greater diameter than the end sections.

10. A reversible plug gauge comprising the combination of a three-part gaging head, a handle adapted to be secured to either end of the head, means for so securing the head to the handle, and three interengaging projections and notches at the abutting ends of the head and handle for forming a tripod support therebetween and preventing relative rotation and looseness between the head and handle, the middle section of the gaging head being of a slightly greater diameter than the end sections.

11. A cylindrical gaging head comprising in combination, a gaging member, a handle, a bolt adapted to secure said gaging member and handle together, a pilot member on said bolt, and means to hold said pilot member and gaging member in alignment.
12. A cylindrical gaging head comprising in combination, a gaging member, a handle, a bolt adapted to secure said gaging member and handle together, a pilot member on said bolt, and a finished cylindrical surface on said bolt adapted to enter said gaging member and pilot member to hold them in alignment.
- In testimony whereof, I hereto affix my signature.

BRYANT H. BLOOD.
